J. E. BUSHNELL

BOOM TRACK FOR BUCKET CONCRETE DISTRIBUTORS

Filed June 18, 1927

Inventor
James E. Bushnell
By his Attorney S. J. Cox

UNITED STATES PATENT OFFICE.

JAMES E. BUSHNELL, OF NORTH PLAINFIELD, NEW JERSEY, ASSIGNOR TO RANSOME CONCRETE MACHINERY COMPANY, OF PLAINFIELD, NEW JERSEY, A CORPORATION OF NEW JERSEY.

BOOM TRACK FOR BUCKET CONCRETE DISTRIBUTORS.

Application filed June 18, 1927. Serial No. 199,665.

The improvements relate primarily to concrete mixing and distributing machines employing a rotary mixing drum with a discharge chute and a cable operated bucket 5 traveling to and from the mixer along an extending boom mounted to swing horizontally and be adjusted vertically. Such machines are most frequently employed on concrete road paving work and are known as 10 pavers. The bucket is suspended from a carriage with suitable rollers employing the bottom flange of the boom—which is usually of I-beam or similar form—as a track, and the concrete is thus distributed by the 15 bucket and dumped on the roadway where it is spread and placed to form the concrete pavement.

Owing to the nature of the materials and their gritty character, and the "dirty" 20 general environment, and the weight of the concrete (a cubic yard weighs approximately 2 tons), the bottom flange of the beam is subject to considerable wear, which not only tends to wear out and weaken the said 25 flange, but in time produces an uneven track resulting in an increased strain on all the parts of the distributing apparatus, waste of power, and other undesirable results. The construction of I-beams and 30 channels or U-beams is also such that the flanges are not absolutely true, and have a more or less outward inclination. All this causes undue wear on the bearings and other parts of the bucket carriage or "trolley" and 35 other parts and makes against efficient and accurate operation.

Although these objectionable features have been well recognized for many years no adequate remedy appears to have been provided, and engineers and workmen engaged 40 in the construction and operation of concrete distributing plants of the character referred to seem to have regarded it as a necessary evil.

The objects of the present improvements are primarily to provide a smooth, even removable and replaceable track for the bucket carriage on the boom; to protect the boom flange against wear and to enable the manufacturer to provide and the user to employ 45 means whereby the track may be made more

satisfactory in various ways. Other objects and advantages will appear to those familiar with apparatus of the character described.

The improvements are illustrated in the 55 accompanying drawings, in which

Fig. 1 is a side elevation of a portion of a distributing boom for a concrete mixer with bucket and its traveling hanger, thereon; Fig. 2 is a vertical cross section taken on the 60 line 2—2 of Fig. 1, with the lower part of the bucket hanger broken away; Fig. 3 is a similar sectional view of a modified form of track; and Figs. 4 and 5 are perspective views of the two forms of track. 65

The boom may be of any desired construction, but the best construction for strength, economy and durability, without great weight, and the preferred construction comprises a pair of channels or U-beams 1 connected by vertically arranged U-beam pieces 2 between them, with their flanges riveted or otherwise secured to the webs of the beams 1. A cut-out portion 2' in the channel sections or spacers 2 permits a bucket 70 operating cable to clear. The rollers 3 or "trolleys" on which the bucket is suspended for travel lengthwise of the boom are also of any desired construction, but preferably of the construction shown, wherein their rims 75 are flat, so as to give a maximum bearing surface on the lower flange 1' of the boom. The bucket hangers 4 are connected with the axles of the rollers 3 in any desired manner, and the bucket 3 is suspended thereby. The 80 particular form of all of the parts just described is not essential to the present improvements. 85

The flanges 1' of the beams 1 are usually tapered, owing to the action of the rolling 90 methods and means employed in their production, and therefore have an outward, downward slope. This normally causes the wheels to assume a position at a slight angle to the vertical and to the plane of the boom, 95 but may be compensated for by forming the hangers 4 as shown in Fig. 2. Nevertheless the load on the bearings 6 should be as nearly vertical as possible, and when roller bearings of well known type are used it is a great 100 advantage to insure this.

On the upper side of the bottom flange 1'

of the boom separate strips 7 or 8 are secured, by means of bolts 9 passing through the flanges and into or through the strips or other suitable securing means. If the bolts 5 extend through the track strips their heads should be countersunk therein so as to be flush with the upper surface thereof and thus avoid any unevenness in the surface over which the wheels or rollers 3 travel. Bolts 10 of any suitable character may be employed, but in all cases they should be removable, so that the track strip may be removed when worn and replaced or inverted so that the side which has not been subjected to wear 15 may be turned uppermost. In the form illustrated in Figs. 2 and 4 the track strip 7 is of uniform gauge or thickness, but in the form illustrated in Figs. 3 and 5 it is tapered or beveled so that when placed on a tapering 20 boom flange its upper surface will be horizontal and the rollers 3 will be in vertical planes with their bearings horizontally disposed. It will be apparent that other modifications may be employed to suit various 25 conditions and variations in the construction of the carriage, its rollers and their bearings. To renew the track strips or reverse them it is only necessary to remove the fastening means and accomplish this, without disturbing 30 the other parts of the distributing apparatus, except that the rollers must be temporarily removed from the track, after which the boom may be swung sidewise and the track strips renewed. It will thus be 35 seen that by the present improvements provision is made for a smooth and true carriage track at all times and that wear or injury thereto may be repaired on the job,

without renewing, or even dismounting the boom.

I claim:

1. In a device of the character described, the combination with a boom having a laterally extending integral bottom flange and a bucket carriage with rollers adapted to travel thereon lengthwise of the boom, of a removable metallic strip having high wearing quality secured along the upper surface of the said flange and in close contact therewith, said strip having a plurality of wearing surfaces and capable of being reversed when one side is worn.

2. In a device of the character described the combination with a boom including a laterally extending bottom flange and a bucket carriage with rollers adapted to travel thereon lengthwise of the boom, of a supplemental strip having high wearing quality supported on and secured through the upper surface of said flange and in close contact therewith.

3. In a device of the character described, the combination with a boom including a laterally extending bottom flange and a bucket carriage with rollers adapted to travel thereon lengthwise of the boom, of a supplemental strip having high wearing quality supported on and secured through the upper surface of said flange and in close contact therewith, said strip having a plurality of wearing surfaces and capable of being turned when one surface is worn.

Witness my hand this 16 day of June, 1927, county of Middlesex, State of New Jersey.

JAMES E. BUSHNELL.
